[57] **CLAIM**

The ornamental design for an combination toothpaste dispenser, cup and toothbrush holder, as shown and described.

DESCRIPTION

FIG. 1 is a top, front, and right side perspective view of a combination toothpaste dispenser, cup and toothbrush holder showing my new design;

FIG. 2 is a front elevational view thereof;

FIG. 3 is a right side elevational view thereof;

FIG. 4 is a left side elevational view thereof;

FIG. 5 is a bottom plan view thereof;

FIG. 6 is a top plan view thereof; and,

FIG. 7 is a rear elevational view thereof.

The broken-line disclosure of a mounting means on the rear is for illustrative purposes only and forms no part of the claimed design.

FIG. 1

FIG. 2

FIG. 3

FIG. 4

FIG. 5

FIG. 6
